AMUSEMENT RIDE APPARATUS

Solomon W. Shepherd, Oakland, Calif.

Application September 26, 1941, Serial No. 412,383

9 Claims. (Cl. 272—36)

This invention relates to apparatus for providing aerial amusement rides.

It is an object of the invention to provide amusement ride apparatus of the type wherein passenger carriers are moved in orbital paths about an elevated horizontal axis, in which the passengers at all times face in directions parallel to the said axis.

Another object of the invention is to provide an amusement ride apparatus, of the type above described, in which the aforesaid horizontal axis of rotation of the passenger carriers is itself revolved about a vertical axis so that the passenger carriers are made to move through complex orbits.

A further object of the invention is to provide a novel and compact drive for effecting the movement of the passenger carriers.

Still another object of the invention is to provide novel means for maintaining the passengers in an upright position with respect to the surface of the ground during all movements of the passenger carriers.

Other objects of the invention and the advantages derived therefrom will be specifically pointed out as the detailed description of the apparatus, hereunto annexed, proceeds; reference being now had to the drawings in which:

Figure 1 is a side elevational view of the complete apparatus with portions of the base being omitted so as to conserve space in the drawings.

Figure 2 is a front elevational view of the structure illustrated in Figure 1.

Figure 3 is a fragmental top plan view, to an enlarged scale, of a portion of the apparatus centered around the upper end of the main support column and the rotor axle.

Figure 4 is a front elevational view of the structure shown in Figure 3. Portions of the view are broken away and other portions thereof are shown in vertical section so as to more clearly bring out the features of internal construction.

Figure 5 is a fragmental side elevational view, drawn to an enlarged scale, of the distal end portion of one of the rotors.

Figure 6 is a front elevational view, partly in vertical section, of the structure shown in Figure 5. The plane in which the view is taken is indicated by the line 6—6 of the latter figure.

Figure 7 is a top plan view of the aerial ride apparatus of my invention.

Describing the invention in detail, the apparatus comprises an axially vertical, tubular support column 7 provided, for stability, with three or more horizontally radiating, ground-engaging, base arms 8 each of which is provided with ver-

tical anchor bars 9 which are removably secured, by bolts 11 to apertured lugs 12 formed on the column 7 at the lower end thereof. The upper end of the column 7, reference being now had to Figure 4, is provided with a separate, rotatable, vertical column extension 13 having at its upper end an integral, axially horizontal, tubular axle 14 mounted thereon and extending equidistantly in opposite directions beyond the axis of the column extension 13. The journal for the column extension 13 comprises a tubular stem 16 attached to the former and extending downwardly into the upper end of the column 7, the stem 16 being engaged in bearings 17 which are pressed, or otherwise secured, in the end of the column. A ball thrust bearing 18, which bears the load of the axle 14 and its attached mechanism, to be described presently, is carried by support rings 19 and 21 mounted, respectively, on the lower end of the column extension 13 and on the upper end of the column 7. Mounted on and extending from both ends of the axle 14 are rotor studs 22 carrying bearings 23 which journal the hubs 24 of the rotors. Each rotor comprises structural steel arms 26 extending in opposite directions from, and connected for rotation with, the hubs 24. Each rotor is provided with a distal end extension 27 which is positioned closer to the axis of the column 7 than the main or central portion of the rotor and is connected with the latter portion of the rotor by a box gusset 28 or similar connecting means. Castings 29 or their equivalent, secured to the extreme outer end of each rotor extension 27, are bored to receive the shanks 31 of carriage studs 32 which project, as shown in the drawings, outwardly with respect to the column 7. Suitable truss rods 30 are provided connecting the arms 26, adjacent their central portions, with the box gussets 28 so as to enhance the rigidity of the arms 26 and to relieve some of the bending strain on the box gussets. A nut 33, or similar means, is provided for securing the shanks 31 in the castings 29. Journaled on the carriage studs 32 are sleeves 34 to the outer ends of which are connected the frames 36 of passenger carriages 37 each equipped with suitable seats. The axis of each carriage is horizontally parallel with the surface of the ground. Struts 38 extend angularly from flanges 39, formed integrally with the sleeves 34, to the frames 36 of the respective carriages; and each sleeve 34 has formed integrally therewith a sprocket 41. It will be seen that when the rotors 26 are moved about the rotational axis thereof, which is the axis of the bearings 23, the carriages 37 will be made to pass

through a circular orbit whose center coincides with the said axis of the bearings. It will also be seen that if the column extension 13 is rotated, while the rotors 26 are rotating, the orbits along which the carriages pass will be complex, being a combination of rotary movements about both horizontal and vertical axes. It will also be seen that, due to the inward offsetting of the outer ends of the rotors, the carriages 31 are brought closer to the axis of the column 7 thereby reducing the width of the apparatus.

Mechanism is provided for driving the rotors 26, which mechanism is best illustrated in Figures 3 ad 4. Depending from the axle 14 is a bracket 42 carrying a drive motor 43 whose drive shaft 44 enters a housing 46 mounted, in any suitable manner such as by the bosses 47, on the column extension 13. The motor drive shaft 44 is fitted with a sprocket 48 meshing with a chain 49 which also engages a larger sprocket 51 carried by a countershaft 52 journaled in the housing 46 and extending therefrom into a gear box 53 which is secured to the housing by suitable means such as the screws 54. Secured to the countershaft 52, within the gear box 53, is a bevel pinion 56 meshing with a pair of bevel gears 57 which are attached to separate jack shafts 58 journaled in, and extending in opposite directions from, the gear box 53. The outer ends of the jack shafts 58 are journaled in bearings 59, carried by the ends of support arms 61 attached to and extending radially from the axle 14, and are fitted with sprockets 62 connected, by chains 63 with, and to drive, larger sprockets 64 carried by the rotor hubs 24. Current to energize the motor 43 is conducted through suitable leads which pass through a tubular post 66 depending from the bottom of the motor 43 and mounted thereon by means of a bracket 67. These leads are connected to spring metal brushes 68 having their anchored ends supported by an insulating sleeve 69 mounted on the lower end of the post 66, the free ends of the brushes 68 bearing against metallic collector rings 71 carried by an insulating sleeve 72 mounted on the stationary column 7. Power supply leads, not shown, may be connected to the respective collector rings 71. It will be seen that, when the drive motor 43 is energized, its drive shaft 44 will rotate the sprocket 48 and will drive the sprocket 51 through the chain 49. This will rotate the countershaft 52 causing its bevel pinion 56 to rotate the bevel gears 57, and consequently the jack shafts 58, in opposite directions to drive the chains 63 thereby rotating the rotors 26 synchronously in opposite directions so as to move the passenger carriages 31 through their circular orbits about a horizontal axis.

Means is provided for maintaining the passenger carriages, during their orbital movement, at all times on an even keel so that the passengers are always seated in an upright position. Secured in, and extending axially outwardly from each rotor stud 22, is a stub shaft 73 secured to which is a fixed stabilizing element or dual sprocket 74 engaged by chains 76 which extend, in opposite directions, along each rotor 26. Referring now to Figures 5 and 6, the chains 76 engage sprockets 77 carried by countershafts 78 journaled in suitable bearings 79 provided in the box gussets 28, the countershafts 78 being also fitted with sprockets 81 which mesh with chains 82 extending outwardly and engaging the sprockets 41 carried by the sleeves 34. The main pair of sprockets 41 and 74 must con-

tain the same number of teeth and the intermediate pair of sprockets 77 and 81 may be smaller or larger than the main pair but must also contain, relatively, the same number of teeth.

5 It will be seen that, since the dual sprockets 74 are fixed and the ratio between the latter sprockets and the sprockets 41 carried by the carriage frame is unity, the passenger carriages will be synchronously rotated with the rotors 26 but in 10 an opposite direction therewith so that the position of the passengers will remain perpendicular to the surface of the ground at all times during the rotation of the rotors 26.

Means is provided for bodily rotating the rotors and their connected passenger carriers about a vertical axis. Extending upwardly through bearings 83 and 84 formed, respectively, on the support ring 19 and in the bottom of the gear case 53, is a shaft 86 provided with a bevel pinion 87, which meshes with the bevel gears 57, and with a pinion 88 which meshes with a ring gear 89 fixed on the bearing support ring 21 or any other convenient stationary portion of the column 7. It will be seen that, during rotation 25 of the countershaft 52, the bevel pinion 87 will be rotated, through the bevel gears 57, thus rotating the shaft 86 and its pinion 88 which will cause the column extension 13 and all of the apparatus, including the rotors 26, carried thereby to rotate bodily about the axis of the column 7. Thus the passenger carriages 31 will follow an orbital path which is the resultant of the rotary movement of the rotors 26, about the horizontal axis of the axle 14, and the rotary movement 30 of the rotors about the vertical axis of the column 7. Thus, depending upon the relative rates of rotation about the aforesaid horizontal and vertical axes, the path described by each carriage 31 may be in the form of a cycloid traced 35 on the periphery of an axially vertical barrel-shaped cylinder whose maximum radius is the distance from the axis of the column 7 to the center of a carriage when the rotors 26 are horizontal, or, in the form of alternately ascending 40 and descending spirals traced on the same cylinder periphery.

While I have shown a common drive motor 43 for effecting both the axially horizontal rotation of the rotors 26 and the axially vertical rotation of the axle 14, it is obvious that separate drive motors may be employed without departing from the spirit of the invention. Thus, if variable speed motors are employed, a wide variety of orbital paths along which the passenger 45 carriers may be passed, can be obtained.

Having thus described my invention in detail, what I claim as new and desire to secure by Letters Patent is:

1. An amusement ride apparatus comprising a 60 vertical column, a horizontal axle mounted on said column and rotatable about the vertical axis thereof, rotors each comprising integral oppositely directed arms radiating from opposite ends of and journaled on said axle, passenger carriages carried by and journaled on the outer ends of said rotor arms, a motor for rotating said axle, means connecting said rotors with and to be rotated in opposite directions, by said motor, means for rotating said passenger carriages counter to the rotation of said rotors and at unity ratio, and means connecting said motor to rotate said axle about the vertical axis of said column.

2. An amusement ride apparatus comprising a 70 vertical column, a horizontal axle mounted on

75

said column and rotatable about the vertical axis thereof, rotors each comprising integral oppositely directed arms radiating from opposite ends of and journaled on said axle, passenger carriages carried by and journaled on the outer ends of said rotor arms, a motor for rotating said axle, jack-shafts carried by said axle, means connecting said jackshafts to be rotated in opposite directions by said motor, means connecting each jack-shaft and a rotor for rotation together, means connecting said axle for rotation by said motor about the vertical axis of said column, and means connecting said passenger carriages for rotation synchronously with and in opposite directions with respect to said rotors.

3. An amusement ride apparatus comprising a vertical column, a horizontal axle mounted on said column and rotatable about the vertical axis thereof, rotors each comprising integral oppositely directed arms radiating from opposite ends of and journaled on said axle, passenger carriages carried by and journaled on the outer ends of said rotor arms, a motor mounted on said axle, jack-shafts carried by said axle, means connecting said jackshafts to be rotated in opposite directions by said motor, means connecting each jack-shaft and a rotor for rotation together, means connecting said axle and said column for relative rotation, and means connecting said passenger carriages for rotation synchronously with and in opposite directions with respect to said rotors.

4. An amusement ride apparatus comprising a vertical column, a horizontal axle mounted on said column and rotatable about the vertical axis thereof, rotors each comprising integral oppositely directed arms radiating from opposite ends of and journaled on said axle, passenger carriages carried by and journaled on the outer ends of said rotor arms, fixed sprockets secured to the ends of said axle, sprockets mounted on said passenger carriages, endless chains tractionally engaging said fixed sprockets and the sprockets of the passenger carriages, a motor mounted on said axle, jack-shafts carried by said axle, gearing connecting said jackshafts with said motor to be rotated in opposite directions by the latter, sprockets, respectively, on said jackshafts and said rotors, endless drive chains connecting the jack-shaft and rotor sprockets, and gearing connecting said axle and said column and driven by said motor for effecting relative rotation between said axle and said column.

5. An amusement ride apparatus comprising a vertical tubular column, annular bearings in the upper end of said column, an upwardly directed column extension axially alined with and journaled in the annular bearings of said upper end of the column, a thrust bearing interposed between adjacent ends of said column and said column extension, a horizontal axle carried by said column extension, said axle at the ends thereof being provided with axially alined bearing studs and fixed sprockets, rotors each comprising arms radiating from said axle and journaled on said bearing studs thereof, drive sprockets secured to and rotatable with said rotors, passenger carriages carried by and journaled at the outer ends of said arms, said passenger carriages each having a drive sprocket mounted thereon and rotatable therewith, chains tractionally engaging the fixed sprockets of said axle and the sprockets of said passenger carriages, a motor carried by said axle, jack-shafts journaled on said axle, means connecting said

motor to drive said jack-shafts simultaneously in opposite directions, sprockets on said jack-shafts, chains tractionally engaging the jack-shaft sprockets and the drive sprockets of said rotors, 5 a gear fixed on said column, a pinion carried by and journaled on said column extension and meshing with said column gear, and means connecting said pinion with and to be rotated by said motor.

10 6. An amusement ride apparatus comprising a vertical tubular column, annular bearings in the upper end of said column, an upwardly directed column extension axially alined with and journaled in the annular bearings of said upper end 15 of the column, a thrust bearing interposed between adjacent ends of said column and said column extension, a horizontal axle carried by said column extension, said axle at the ends thereof being provided with axially alined bearing studs and fixed sprockets, rotors each comprising arms radiating from said axle and journaled on said bearing studs thereof, drive sprockets secured to and rotatable with said rotors, passenger carriages carried by and journaled at the outer ends 20 of said arms, said passenger carriages each having a drive sprocket mounted thereon and rotatable therewith, chains tractionally engaging the fixed sprockets of said axle and the sprockets of said passenger carriages, a motor carried by said axle, jack-shafts journaled on said axle, means connecting said motor to drive said jackshafts simultaneously in opposite directions, sprockets on said jack-shafts, chains tractionally engaging the jack-shaft sprockets and the drive sprockets of said rotors, 25 a ring gear secured to and concentric with the upper end of said column, a shaft journaled on said column extension, a pinion carried by said shaft and meshing with said ring gear, and means connecting said pinion shaft to be rotated by said motor.

30 7. An amusement ride apparatus comprising a vertical tubular column, annular bearings in the upper end of said column, an upwardly directed column extension axially alined with and journaled in the annular bearings of said upper end 35 of the column, a thrust bearing interposed between adjacent ends of said column and said column extension, a horizontal axle carried by said column extension, said axle at the ends thereof being provided with axially alined bearing studs and fixed sprockets, rotors each comprising arms radiating from said axle and journaled on said bearing studs thereof, drive sprockets secured to and rotatable with said rotors, 40 passenger carriages carried by and journaled at the outer ends of said arms, said passenger carriages each having a drive sprocket mounted thereon and rotatable therewith, chains tractionally engaging the fixed sprockets of said axle and the sprockets of said passenger carriages, a motor carried by said axle, a gear box mounted on said axle, said gear box having therein a countershaft provided with a bevel pinion and bevel gears meshing with said bevel pinion and mounted 45 on jack-shafts extending in opposite directions from said gear box and directed toward the opposite ends of said axle, said gear box also having therein a bevel drive pinion meshing with said bevel gears and mounted on a drive shaft extending downwardly from said gear box to a position adjacent the upper end of said column, means connecting said countershaft to be rotated by said motor, sprockets on said jack-shafts, chains connecting the jack-shaft sprockets and the drive sprockets of said rotors, 50 a ring gear secured to and concentric with the upper end of said column, a shaft journaled on said column extension, a pinion carried by said shaft and meshing with said ring gear, and means connecting said pinion shaft to be rotated by said motor.

cured to said column concentric with and adjacent the upper end thereof, and a pinion secured to and rotatable with said drive shaft, said pinion being in mesh with said ring gear.

8. An amusement ride apparatus comprising a vertical tubular column, annular bearings in the upper end of said column, an upwardly directed column extension axially aligned with and journaled in the annular bearings of said upper end of the column, a thrust bearing interposed between adjacent ends of said column and said column extension, a horizontal axle carried by said column extension, said axle at the ends thereof being provided with axially aligned bearing studs and fixed sprockets, rotors each comprising arms radiating from said axle and journaled on said bearing studs thereof, drive sprockets secured to and rotatable with said rotors, said rotor arms, at the outer ends thereof, being provided with extensions horizontally offset toward the axis of said column, countershafts journaled in said rotor arms intermediate the ends thereof and the axis of said axle, sprockets secured to and rotatable with said countershafts, passenger carriages carried by and journaled at the outer ends of said rotor arm extensions, said passenger carriages projecting outwardly from said rotor extensions away from said axis of the column and each having a sprocket secured to and rotatable therewith, looped drive chains tractionally engaging the fixed sprockets of said axle and sprockets of said countershaft and also the sprockets of said passenger carriages and sprockets of said countershaft, a motor mounted on said axle, jack-shafts journaled on said axle each having a sprocket secured to and rotatable therewith, chains tractionally engaging said jack-shaft sprockets and the drive sprockets of said rotors, gearing connecting said jack-shafts with and to be rotated in opposite directions by said motor, and gearing interposed between adjacent ends of said column and said column extension and connected to be driven by said motor so as to effect relative rotation between said column and said column extension.

9. An amusement ride apparatus comprising a vertical tubular column, annular bearings in the upper end of said column, an upwardly directed column extension axially aligned with and

journaled in the annular bearings of said upper end of the column, a thrust bearing interposed between adjacent ends of said column and said column extension, a horizontal axle carried by said column extension, said axle at the ends thereof being provided with axially aligned bearing studs and fixed sprockets, rotors each comprising arms radiating from said axle and journaled on said bearing studs thereof, drive sprockets secured to and rotatable with said rotors, said rotor arms, at the outer ends thereof, being provided with extensions horizontally offset toward the axis of said column, countershafts journaled in said rotor arms intermediate the ends thereof and the axis of said axle, sprockets secured to and rotatable with said countershafts, passenger carriages carried by and journaled at the outer ends of said rotor arm extensions, said passenger carriages projecting outwardly from said rotor extensions away from said axis of the column and each having a sprocket secured to and rotatable therewith, looped drive chains tractionally engaging the fixed sprockets of said axle and sprockets of said countershaft and also the sprockets of said passenger carriages and sprockets of said countershaft, a motor mounted on said axle, jack-shafts journaled on said axle each having a sprocket secured to and rotatable therewith, chains tractionally engaging said jack-shaft sprockets and the drive sprockets of said rotors, gearing connecting said jack-shafts with and to be rotated in opposite directions by said motor, a ring gear secured to said column adjacent the upper end thereof, a pinion journaled on said column extension and meshing with said ring gear, means connecting said pinion to be rotated by said motor, a plurality of circular current conductor rings mounted concentrically on and insulated from said column and positioned adjacent said ring gear, a tubular post secured to and depending from said column extension through which current conductors connected with said motor may be passed, and flexible current-collecting brushes carried by and insulated from said post, said brushes being in contact with said circular current conductor rings and being electrically connected with said current conductors of said motor.

SOLOMON W. SHEPHERD.
